United States Patent Office.

GEORGE H. GARRETT, OF ST. LOUIS, MISSOURI, ASSIGNOR TO
RICHARD P. GARRETT, OF SAME PLACE.

Letters Patent No. 85,440, dated December 29, 1868.

IMPROVEMENT IN MOULDING PIPE.

The Schedule referred to in these Letters Patent and making part of the same.

To all whom it may concern:

Be it known that I, GEORGE H. GARRETT, of St. Louis, in the county of St. Louis, and State of Missouri, have made certain new and useful Improvements in Apparatus for Moulding Pipes and other cylindrical castings; and I do hereby declare that the following is a full and clear description thereof, reference being had to the accompanying drawings, and to the letters of reference marked thereon.

The object of this invention is to construct an improved apparatus for moulding pipes or other round or cylindrical castings, the moulds to be rammed on their sides, as hereinafter more fully described.

The invention consists of an improved flask, into which the sand is to be rammed, and a revolving mould or pressing-device, which presses and forms the sand into the required shape for the article to be cast.

To enable those skilled in the art to make and use my improved apparatus, I will proceed to describe its construction and operation.

Figure 1 of the drawings is a side elevation of the improved apparatus, including both the flask and the ramming-device.

Figure 2 is a top plan of the same.

Figure 3 is a plan of the flask alone.

Figure 4 is a transverse sectional elevation of the flask and ramming-device.

Figure 5 is a sectional elevation of the flask alone.

The flask A is to be made of metal, and is to be accurately constructed, so as to form just one-half, or one even fractional portion of a whole flask, and to this end the straight or joining side of the flask will be planed off perfectly straight and true, so as to fit accurately against the corresponding joint or joints of the remaining piece or pieces of the whole flask.

These flask-sections are to be made the exact counterparts of each other, so that any two of the same series of flasks may be put together and accurately fit each other, so as to form a perfect flask.

Each flask-section, then, must be a segment of a circle, so that when the whole flask is put together, it will form a perfect cylinder.

The end-parts of the flask-pieces are to be accurately turned out, so as to form seats at *a* for the bearings of the cores.

The sides of each of the flask-pieces A are provided with holes, as at *a'*, for the insertion of trunnion-pins, by means of which to lift the flask.

These holes should be so located as to cause the flask-section to be counterpoised on the trunnions inserted therein, when the said flask-section is filled with sand and elevated by means of the said trunnions.

There are also other trunnion-holes, as at *a''*, which are formed partly in each of the flask-sections, as shown in fig. 1.

When the flask-sections are bolted together, as here-

inafter more fully described, the whole flask may be lifted by its trunnions at *a'*, on which the whole flask will balance, suitable machinery, of course, being used for the purpose of raising the said flask.

The holes at *a'* and *a''* are accurately bored out, so that the same trunnion-pin may be fitted into either place.

A rib, *a''*, as shown best in fig. 5, extends along each side of the flask-section, parallel with and close to its straight face, for the purpose of holding the sand in the said flask-section.

The moulding-apparatus consists of a roller, B, and a sweep, C, with various devices for operating the same, all of which are secured to and operated from the frame D, which is neatly and accurately fitted to the flask-section A, and secured thereto by means of the set-screws *d*.

The holes for the screws *d* must be bored into the frame D and the flask A, from marks made from the same templet, so as to make any two sections of the flask to fit together at random, and in the same manner the frame D and its appendages may be applied to any flask-section with equal exactness.

In the end-pieces of the frame D, bearings are provided for the journals of a central shaft, E, the said bearings to be concentric with the flask-section.

One end of the shaft E overhangs the end of the frame D and flask A, and is provided with a hand-wheel, E', by means of which to turn it.

The roller B has its bearings in the radial arms B', which project from one side of the central shaft E, and the sweep C is secured to the opposite side of the said central shaft by means of similar radial arms, C'.

The periphery of the roller B is to be turned in whatever shape or form it is desired to give the completed pipe or casting.

The arms B', by means of which the roller is to be attached to the shaft E, are made adjustable, as to length, by means of movable bearing-boxes, *b*, and set-screws, *b'*, or cams might be used in lieu of the said screws.

The said boxes *b* are secured to the ends of the arms B' by means of the said set-screws, or their equivalent devices, and by them they may be moved in or out, so as to increase or diminish the distance between the centres of the roller B and the shaft E, for the purpose hereinafter more fully explained.

The sweep C is attached to the central shaft E by means of arms, C', these arms having their inner ends formed in the shape of a band, which is made to surround the shaft, which is rounded at that part, so as to permit the said arms to be turned around on the shaft, for the purpose of changing the position of the sweep, or of turning the sweep around without turning the shaft.

The arms C' may be securely fixed to the shaft E at any point by means of the set-screws *c*.

In constructing the flask, an opening may be made

along one entire side of one of its sections for a gate, or openings may be made, at a' , in one of its ends, for this purpose. These openings, of course, would have to be covered with some moulders' facing-material to prevent the molten metal from cutting therein into the metal flask. A thin rim of sand would have to be interposed between the body of the casting and the core-print, to keep the molten metal from the flask at that point.

The apparatus, constructed as above described, is to be operated as follows:

One of the flask-sections is to be filled around its outer part with tempered sand, and pressed into nearly the shape of the mould, with the moulder's hands, or by other suitable means. Then the frame D and its appendages are to be placed on the flask, and secured thereto by means of the set-screws d .

At this time the roller B may or may not be in its place in the machine. If it should be out, the screws c may be loosened, and the sweep C moved around the shaft E by hand, thereby scraping off the sand from the high places, and filling up the cavities.

When the sand is properly shaped in this manner, the roller B will be brought into requisition, and at first it will be drawn up as close to the shaft E as its adjustable arms will allow it to go.

The sweep C will then be secured to the shaft E by means of the screws c , and the shaft E will be revolved about its axis by means of the hand-wheel E'.

At each successive revolution of the shaft E, the roller will be set further out, by means of the set-screws b' , until its outer limit (which must be defined by a fixed or adjustable stop) shall have been reached.

As the roller is pressed over the sand of the mould in this manner, the sand will be properly formed and

hard pressed by the said roller, for the purposes of casting therein.

As new sand is added, the sweep C will shape and form it off in the proper manner, so that the roller may act upon it with a uniform pressure, and all parts of the mould will thereby be pressed to an equal degree of hardness.

By having the centres of the shaft E accurately fixed in the frame D, and the frame D secured to the flask-sections in the accurate manner hereinbefore described, it is evident that the moulding of each flask-section in this manner will be a perfect segment of a circle.

Should a greater length of casting be desired than can be readily moulded by one length of roller B, the flask may be made long enough for the desired purpose, and then, after one end shall have been moulded, the apparatus may be moved to the other end of the flask.

Should the mould be a very large one, the wheel E' may be required to be a cog-wheel, and acted upon by a small pinion, in order to secure power enough to turn the roller B around in the mould.

Having described my invention,

What I claim, is—

1. The flask A, when provided with an adjustable frame-work, D, and a pressing-roller, B, for moulding and shaping the sand, in the manner herein shown and described.

2. The roller B, and its adjustable arms B', when arranged and operated as described and set forth.

GEO. H. GARRETT.
